DESIGN FOR A TEXTILE FABRIC

Eugene Irving Hanson, New York, N. Y.

Application October 10, 1936, Serial No. 65,236

Term of patent 3½ years

To whom it may concern:

Be it known that I, Eugene Irving Hanson, a citizen of the United States, residing in New York city, county and State of New York, whose post office address is 119 West 40th Street, New York, N. Y., have invented a new, original, and ornamental Design for a Textile Fabric, of which the following is a specification, reference being had to the accompanying drawing, forming part thereof, wherein the figure is a plan view of a textile fabric showing my new design, embodying the design unit.

I claim:

The ornamental design for a textile fabric substantially as shown and described.

EUGENE IRVING HANSON.
